UNITED STATES PATENT OFFICE

2,413,585

CUTTER CHAIN

Leon E. Simmons, Claremont, N. H., and Harry H. Vanderzee, Michigan City, Ind., assignors to Joy Manufacturing Company, a corporation of Pennsylvania

Application August 18, 1943, Serial No. 499,094

4 Claims. (Cl. 262—33)

1

This invention relates to cutter chains and more particularly to an improved mining machine cutter chain especially designed for use in the cutting of coal or the like.

An object of the present invention is to provide an improved cutter chain. Another object is to provide an improved socket arrangement for a chain block of a cutter chain whereby cutter bits of different types may be positioned and held in the block sockets. A further object is to provide an improved chain block designed interchangeably to receive a detachable holder for a small plural pointed reversible cutter bit or the shank of a standard single pointed shanked bit. Yet another object is to provide an improved bit socket arrangement adapted to receive portions of cutter bits of different widths while providing adequate support for the same. A still further object is to provide an improved chain block socket shaped to receive interchangeably the inactive cutting portion of a small plural pointed reversible cutter bit or the shank of a standard single pointed cutter bit, and having projections which serve properly to position the standard bit shank. Still another object is to provide an improved chain block socket having relatively large flow passages for dirt and cuttings thereby to reduce the possibility of clogging and sticking of the parts received in the socket. Other objects and advantages of the invention will, however, hereinafter more fully appear.

In the accompanying drawing there is shown for purposes of illustration one form which the invention may assume in practice.

In this drawing:

Fig. 1 is a side elevational view, with parts broken away in section, of a portion of a cutter chain constructed in accordance with an illustrative embodiment of the invention.

Fig. 2 is a cross sectional view taken substantially on line 2—2 of Fig. 1, looking toward the front of the chain block.

Fig. 3 is a view in longitudinal vertical section taken substantially on line 3—3 of Fig. 2.

Fig. 4 is a horizontal sectional view taken substantially on line 4—4 of Fig. 3.

Fig. 5 is an enlarged cross sectional view, showing the improved block socket.

Fig. 6 is a perspective view of a small plural pointed reversible cutter bit.

Fig. 7 is a side elevational view of the cutter bit holder.

Fig. 8 is a top plan view of the bit holder.

Fig. 9 is a view in longitudinal vertical section, similar to Fig. 3, showing a standard, single-pointed shanked cutter bit in the block socket.

Fig. 10 is a horizontal sectional view taken substantially on line 10—10 of Fig. 9.

In this illustrative embodiment of the invention there is shown a cutter chain generally of

2

a conventional design comprising chain blocks 1 which are pivotally connected at 2 to strap links 3. These strap links have usual gibbs 4 adapted for reception in the guideway of a conventional cutter bar. Each chain block has a lateral lug 5 in which the improved socket generally designated 6, is formed. This socket extends through the block lug at right angles to the path of travel of the cutter chain and extending longitudinally of the lug and opening into this socket are usual threaded bores 7 adapted selectively to receive a conventional set screw 8. Evidently, the improved socket arrangement may be embodied in cutter chains of types other than that disclosed.

The improved chain block socket 6 is adapted interchangeably to receive a holder 9 for a small plural pointed reversible cutter bit 10 or a shank 11 of a standard single pointed shanked bit 12. As clearly shown in Fig. 5, the block socket is generally rectangular in shape in cross section and has parallel plane front and rear end walls 13 and 14 and is centrally laterally enlarged at 15. The socket enlargement has curved side walls 16, 16 which terminate at projections 17, extending inwardly from the parallel vertical side walls 18, 18 of the socket. This arrangement provides enlarged end recesses 19 between the projections 17 and end socket walls at each end of the socket. The projections 17 have parallel plane inner surfaces 20. This socket may be formed in various manners but is herein preferably formed by drilling and broaching operations of well-known types. The threaded bores 7 extend longitudinally through the parallel end walls 13, 14 of the socket so that the set screw received in one of the bores may be adjusted to enter at its inner end the socket.

The cutter bit has a body generally T-shaped in cross section and provided with relatively inclined cutting portions having front cutting faces 21, 21 lying in the sides of an obtuse angle and terminating in cutting points 22 at the opposite extremities of the bit. The bit holder 9 has a shank 23 generally rectangular in shape in cross section and is vertically slotted at 24 at its forward side to receive the rear flange 25 of the T-shaped bit body. The forward surfaces 26 of the bit holder at the opposite sides of the vertical slot 24 engage the rear surfaces of the lateral flanges 27 provided by the head of the T. As shown in Fig. 3, the bottom wall 28 of the holder slot is shaped to conform to the curved rear surface 29 of the flange 25 of the bit body. When the holder shank is inserted in bit holding position in the block socket as shown in Fig. 3, the rear surface of the holder shank engages the rear socket wall 14 and the head 30 of the holder rests at 31 against the outer surface of the chain block lug. When the cutter bit is positioned as shown in Fig. 3, its active cutting por-

tion projects forwardly and outwardly with respect to the chain block and its inactive cutting portion lies inwardly within the block socket. Since the lateral flanges 27 of the cutter bit project outwardly to provide a front cutting face of a width substantially wider than the width of the shank 11 of a standard single pointed bit, the end socket enlargement 19 is provided, and the side flanges of the inactive cutting portion of the bit are received in this enlarged recess in the manner shown in Fig. 4. When the parts are so positioned, the set screw 8 is adjusted into a position wherein its inner end engages the front face of the inactive cutting portion of the bit to clamp the bit flanges 27 tightly against the front surface of the holder. Thus the bit and holder are held firmly in position on the block.

Upon removal of the cutter bit and holder, shown in Fig. 3, from the block socket, the shank 11 of a standard single pointed reversible bit 12 may be inserted in the socket in the manner shown in Fig. 9. The rear surface of the bit shank 11 abuts the rear end wall 14 of the socket and the set screw 8, when tightened, engages the front surface of the bit shank to secure firmly the cutter bit in cutting position on the block. Since the shank of the standard single pointed bit is of less width than the width of the cutting face of a small plural pointed reversible cutter bit, the projections 17 are provided to engage the sides of the bit shank 11 in the manner shown in Fig. 10 so that any substantial looseness of the shank in the socket is prevented.

Regardless of whether the small plural pointed reversible cutter bit or the shank of the standard single pointed bit is positioned in the block socket, the parts may be reversed on the block so that the chain may operate as a reversible chain. Upon such reversal of the parts, the set screw 8 is removed from its threaded bore in the block lug and is inserted in the other threaded bore. The reversal of the parts shown in Fig. 3 is effected simply by loosening the set screw, removing the bit and holder from the block socket, turning the bit and holder completely around, and reinserting them into the block socket. The reversed set screw is then tightened to clamp the bit and holder firmly in position. The standard single pointed shanked bit shown in Fig. 9 may be reversed simply by loosening the set screw, withdrawing the bit shank from the socket, turning the bit completely around, and reinserting the bit shank into the socket. The reversed set screw is then tightened to clamp the bit shank firmly in position.

As a result of this invention, simply by the reshaping of the chain block socket it is possible to position different types of cutter bits on the chain block. By the provision of the novel socket shape having an end enlargement and side projections, it is possible interchangeably to position the holder of a small plural pointed reversible cutter bit or the shank of a standard single pointed cutter bit in the chain block socket. The socket arrangement is relatively simple so that the socket of a standard chain block may be easily modified to receive either the detachable cutter bit holder or the standard shanked bit. Other advantages of the invention will be clearly apparent to those skilled in the art.

While there is in this application specifically described one form which the invention may assume in practice, it will be understood that this

form of the same is shown for purposes of illustration, and that the invention may be modified and embodied in various other forms without departing from its spirit or the scope of the appended claims.

What we claim as new and desire to secure by Letters Patent is:

1. In a cutter chain, a support having a socket provided with a relatively wide portion and a communicating relatively narrow portion having inner lateral surfaces spaced longitudinally of said support with respect to said wide portion, a cutter bit having a relatively wide cutting portion received in said wide portion of said socket, and a detachable holder engaging said bit for holding the latter in cutting position on said support with said relatively wide portion in said socket, and having a relatively narrow portion received in said narrow portion of said socket with the inner lateral surfaces of the latter engaging the outermost lateral surfaces of said narrow holder portion.

2. In a cutter chain, a support having a socket provided with a relatively wide front portion and a relatively narrow portion located rearwardly of said front portion and having inner lateral surfaces, a cutter bit provided with a relatively wide front cutting portion and a relatively narrow rearward portion, said wide bit portion received in said wide portion of said socket and said narrow rearward bit portion projecting into said narrow socket portion, and a detachable holder for holding said bit in cutting position on said support and having a socket for receiving said narrow rearward portion of said bit, and having a shank fitting said narrow portion of said support socket with the inner lateral surfaces of the latter engaging with the outermost lateral surfaces of said holder shank.

3. In a cutter chain, a support having a socket provided with a relatively wide portion and a communicating relatively narrow portion having lateral surfaces spaced inwardly from the sides of said wide portion, said narrow portion being spaced longitudinally of said support with respect to said wide portion, a cutter bit having a relatively wide cutting portion received in said wide socket portion, and a detachable holder engaging said bit for holding the latter in cutting position on said support, said holder engaging said bit rearwardly of said wide cutting portion and having a relatively narrow portion received in said narrow socket portion with the inner lateral surfaces of the latter engaging the outermost lateral surfaces of said narrow holder portion.

4. In a cutter chain, a support having a socket provided with a relatively wide front portion and a relatively narrow portion located rearwardly of said front portion and having lateral surfaces spaced inwardly from the sides of said front portion, a cutter bit having a front cutting portion received in said wide socket portion, said bit projecting rearwardly into said narrow socket portion, and a detachable holder for holding said bit in cutting position on said support and engaging and positioning said rearwardly projecting portion of said bit, and having a shank received in said narrow socket portion with the inner lateral surfaces of the latter engaging the outermost lateral surfaces of said holder shank.
